PRECISION CONDENSER ADJUSTER

Victor Clarke, Coral Gables, Fla.

Application July 9, 1937, Serial No. 152,749

5 Claims. (Cl. 74—395)

This invention relates to a precision adjusting device for instruments and the like and, by way of example, may be applied to the tuning mechanism of compact radio transmitters and receivers in which the adjusting mechanism is placed within a comparatively small space.

An object of the invention is to produce an adjusting construction of small size which allows extremely accurate micrometric adjustment of a movable element.

One form of device embodying the invention may be utilized in conjunction with an oscillator coil and associated variable condenser in a radio transmitter. The variable condenser may be positioned in the interior of the coil in order to conserve space, and the adjusting mechanism may be located at the top of the coil and associated with the condenser shaft.

The precision adjuster generally consists of a resilient member tending to displace the condenser shaft angularly in one direction; angular displacement being resisted and controlled by means of a micrometrically adjustable member.

In one form of the invention, the condenser shaft may be provided with a lever which is engaged by a coil spring normally urging the lever and the condenser shaft in one direction. The micrometric means may suitably consist of a set-screw which bears against the opposite side of the arm and upon adjustment causes a limited angular movement of the arm and the condenser shaft. If desired, the set-screw may be calibrated so that a known variation in capacity of the condenser may be obtained by rotating the set-screw through one or a fraction of a complete revolution.

This construction has many advantages, such as for example, small and compact size, and the ability to be adjusted with extreme accuracy and to retain the accurate adjustment over long periods of time without the necessity of recalibrating or readjusting.

Other advantages will be apparent from the description of a typical form of adjusting a mechanism embodying the invention, such as that disclosed in the accompanying drawing, in which:

Figure 1 is a top plan view of an oscillator coil enclosing a variable condenser and the condenser adjusting device of the present invention;

Figure 2 is a side view of the oscillator coil, partly broken away to show details of the adjusting mechanism, and

Figure 3 is a view in section taken on line 55 3—3 of Figure 1.

In the form of the invention illustrated, the adjusting mechanism is disclosed as applied to a variable condenser 10, located in the interior of a coil 12, for use in transmitters or receivers operable on several frequencies. The coil 10 may be of any desired type and is illustrated as having a number of turns of wire 14, supported on a cylindric tube 16 of insulating material and being provided with prongs 18 engageable in a socket (not shown) in a radio transmitter or receiver.

For convenience in allowing interchangeable use of coils tuned to a definite frequency and to render the coil unit as compact as possible, the variable condenser 10 may be supported on the base of the coil 12 and is connected in a known manner to the coil terminals. Supported in the upper portion of the coil form 16 is a cross-bar 20 provided with up-turned ends 22, which are retained in engagement with the walls of the tube 16 by means of bolts or set-screws 24. The cross-bar 20 may be provided with a central aperture 26 through which passes a collar 28 forming a part of the frame of the condenser 10. The bar 20 and condenser 10 may be locked together by means of nuts 30, threaded on the collar 28 on opposite sides of the bar.

The condenser shaft 32 passes through the collar 28 and is adapted to receive on its outer end a lever 34 provided with a bore 36 and split end 38, the arms of which may be drawn together by a set-screw 40 to grip the condenser shaft 32. The opposite end of the lever 34 is provided with an enlarged disk-like portion 42, which is adapted to bear against a set-screw 44, threaded in one arm 46 of a yoke 48 fixed to the bar 20. The set-screw 44, if desired, may be calibrated and provided with indicia so that each turn or fraction of a turn will produce a predetermined variation in the capacity of the condenser by rotation of the condenser shaft 32. The enlarged arm portion 42 is urged against the set-screw 44 by a coil spring 50 disposed between the portion 42 and another arm 52 on the yoke 48. The arm 52 may be provided with an inwardly directed stud 54 which is received within the spring 50. The enlarged portion 42 of the lever may be provided also with a recess for receiving the opposite end of spring 50, thereby cooperating with the stud 54 to retain the spring in an operative position. To permit adjustment of the condenser, the tube 16 may be provided with apertures 56 and 58 which are in alignment with set-screws 44 and 40 respectively, so that

55

an implement may be inserted for rotating the set-screws.

The condenser 10 may be adjusted to desired capacity by rotating the condenser shaft 32 with the lever loosely supported upon it to approximately the final adjusted position. The set-screw 40 is then tightened to clamp the lever 34 tightly to the shaft 32. Thereafter, the set-screw 44 may be adjusted by a suitable tool to produce a very fine regulation of condenser 10, to the capacity desired. The adjusting set-screw 44 may be clamped in yoke arm 46 by means of a screw 60 spanning a split 62 communicating with the threaded aperture in the arm 46.

Where extreme accuracy is required over a wide temperature range, an error will be introduced with the use of the more common metals or alloys due to thermal expansion, or contraction, of various parts of the condenser adjuster and especially the set-screw 44. This error can be minimized by the use of some material having a low coefficient of temperature expansion such as Invar. Another detail of construction to eliminate the effect of expansion in the lever is to design the parts so that the plane of the surface of the lever, which comes in contact with the set-screw, goes through the center line of the shaft to be controlled.

It will be understood from the above description that I have produced an effective and extremely accurate mechanism for adjusting the movable element of any form of instrument or the like. It will also be understood that the construction illustrated may be varied, as desired, without departing from the invention. Therefore, the embodiment disclosed should be considered illustrative only, and not as limiting the scope of the claims.

I claim:

1. In an adjusting device, the combination of a shaft, a lever fixed to said shaft and angularly adjustable with relation thereto, a yoke member, a set-screw threaded into said yoke and having a free end engaging said lever, and resilient means engaging the yoke and the lever for urg-

ing the lever into engagement with the free end of the set-screw.

2. In an adjusting device, the combination of a shaft, a lever fixed to said shaft and angularly adjustable with relation thereto, a yoke member, a set-screw threaded into said yoke and engaging said lever to vary the angular displacement of the shaft and a coil spring bearing against said lever and said yoke for urging the lever against the set-screw.

3. In an adjusting device, the combination of a support, a shaft mounted in said support, a yoke member having spaced arms mounted on said support, a lever adjustably mounted on said shaft and disposed between the arms of the yoke, means mounted on one of the yoke arms and adjustable relatively thereto engaging the lever to vary the angular displacement of the shaft, means for locking in adjusted position the means to vary the angular displacement of the shaft and resilient means bearing against the lever and the other yoke arm to urge the lever into engagement with adjustable means.

4. In an adjusting device, the combination of a support, a shaft mounted in said support, a yoke member having spaced substantially parallel arms mounted on said support, a lever adjustably mounted on said shaft and disposed between the arms of the yoke, a screw threaded through one of the arms and engaging the lever to vary the angular displacement of the shaft, and resilient means bearing against the lever and the other arm of the yoke to urge the lever against the set-screw.

5. In a precision adjusting device, the combination of a support, a shaft mounted in said support, a yoke member having spaced arms mounted on the said support, a lever adjustably mounted on said shaft and disposed between the arms of the yoke, a screw threaded through one of the arms and engaging the lever to vary the angular displacement of the shaft, and a coil spring bearing against the lever and the other yoke arm to urge the lever against the set-screw.

VICTOR CLARKE. 45
